UNITED STATES PATENT OFFICE.

EDGAR H. CLARK, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed October 4, 1918. Serial No. 256,841.

To all whom it may concern:

Be it known that I, EDGAR H. CLARK, a citizen of the United States, residing at New York, in the county of New York and State 5 of New York, have invented certain new and useful Improvements in Telephone-Exchange Systems, of which the following is a full, clear, concise, and exact description.

This invention relates to telephone systems employing automatic switches.

The present invention has for its purpose the provision of an improved signaling system in which indicating devices are controlled over a metallic circuit by impulses of 15 various characteristics transmitted over said circuit.

In its more specific embodiment, the present invention is employed in an automatic telephone system in which calling lines terminating in a semi-automatic telephone exchange may be connected to called lines terminating at a manual exchange. In such a system an A operator at the semi-automatic exchange, after connecting her answering 20 cord to the calling line, sets one or more automatic switches under the control of a sending device, to extend the calling line to a B operator's position. It is then necessary in completing the call to indicate the number of 25 the wanted subscriber to the B operator. In the present disclosure the wanted number is indicated by sets of lamps, a set of lamps being provided for each digit or character of 30 the wanted number. These lamps are selectively operated in response to the operation 35 of a sending device which is variably controlled by the A operator.

One feature of the invention consists in the control of an indicating device by impulses varying in direction or polarity.

Another feature of the invention consists in the control of an indicating device by impulses of current of different values or strength.

These and other features of the invention 45 will appear in the accompanying drawing and description together with the appended claims.

The drawings, with Fig. 2 placed below 50 Fig. 1 and with Fig. 3 placed at the right of Fig. 2, diagrammatically represent a portion of a telephone system employing the present invention. Fig. 1 shows a calling subscriber's substation and 55 line, with brushes of a district selector at the

A operator's position, a calling plug and jack at the B operator's position and a called subscriber's substation apparatus and line. Within the small dotted rectangle at the left-hand side of Fig. 1 there are shown the 60 brushes of a cord finder switch which operate to connect an idle sending device to a cord circuit which has been connected to the calling line. Within the large dotted rectangle at the right-hand side of Fig. 1 there 65 are shown the operator's key set and the registers of the sending device for controlling the transmission of impulses to the number indicating device. Within the dotted enclosure in the middle of Fig. 1 there is 70 shown an impulse transmitting device, which, under the control of the registers, transmits various combinations of impulses to actuate the number indicating device. In Fig. 2 there are shown the various relays 75 which control the lighting of the proper stations lamp, as well as the switching relays which operate to control the actuation of the thousands, hundreds, tens and units indicating devices in proper sequence. Fig. 3 80 in its lower right-hand corner shows the lamps and controlling relays for indicating the thousands digit, at the lower left-hand corner of Fig. 3, the hundreds; at the upper left-hand corner of Fig. 3, the tens; and at 85 the upper right-hand corner of Fig. 3, the units lamps and the relays for controlling the same.

In this disclosure the showing of the apparatus and circuits for selecting the B operator's position has been abbreviated, but it may be of the character of the system disclosed in the patent to Lundell, No. 1,168,319 of January 18, 1916, or it may be similar to the system shown in applicant's copending 95 application, Serial No. 178,468, filed July 3, 1917.

The trunk selecting switch referred to in the description may be of the type illustrated in the patent to Craft and Reynolds, No. 1,123,696 of January 5, 1915, although it will be readily understood that any automatic selector switch can be employed in this system without departing from the spirit of the invention.

In the description reference is made to sequence switches and registers, the structure of which may be similar to that shown in the patent to Reynolds and Baldwin, No. 1,127,808 of February 9, 1915.

105

110

In general, the present system comprises a set of operator's keys which control sequence switch registers, all of which are shown in the dotted rectangular at the right in Fig. 1.

5 A device for sending impulses as determined by the sequence switch registers is shown in the upper left-hand dotted enclosure in Fig. 1, and an arrangement of relays for receiving these impulses shown in Figs. 2 and 3.

10 In Fig. 2 there are shown three relays in series, Nos. 201, 202 and 203, which respond directly to the transmitted impulses. These relays in turn control a combination of two relays 207 and 209 which have a peculiar in-

15 teraction, as will be hereinafter more fully explained. A set of relays, such as 206 and 210, is provided for each one of the digits of the called number and these relays are controlled through the interaction of the relays

20 207 and 209.

There is provided a set of indicating lamps for each one of the digits of the called number, each set of lamps being controlled by a set of lamp controlling relays A, B, 25 C and D. As shown in Fig. 3, the set A', etc., controls the thousands lamps, the set A², etc., controls the hundreds lamps, the set A³, etc., controls the tens lamps, and the set A⁴, etc., controls the units lamps.

30 As shown in Fig. 2 the set A, B and C controls the stations lamps.

The impulses transmitted by the device controlled by sequence switch 114 in Fig. 1 are in the nature of a code, these impulses

35 being in a continuous train of positive and negative impulses of light and heavy current. The impulses of light current are produced through a grounded battery current flowing through the resistance 142 to

40 the combination of sequence switch contacts 133 and 139. The impulses of heavy current are produced by grounded battery current flowing through this same resistance 142 and the low resistance 130 in parallel,

45 the parallel connection being effected through the various register sequence switch contacts and sequence switch contacts controlled by the switch 114 shown in an arrangement above the resistance 130. For

50 convenience, hereinafter the heavy current will be spoken of as produced by the low resistance 130, the high resistance 142 being left out of consideration since it is permanently connected to the contacts 133 and 139.

55 The code of impulses is shown diagrammatically in the upper part of Fig. 2 under the two headings "Numerical code" and "Stations code". The light lines above the base lines represent impulses of light positive current; the heavy lines above the base lines represent impulses of heavy positive current; and the light and heavy lines below the base lines represent respectively im-

60 pulses of light and heavy negative current.

65 Each train of impulses consists of four such

positive and negative impulses in a different combination, always starting, however, with a positive impulse and ending with a negative impulse so that several of these trains may be merged into one long series of impulses.

As will hereinafter appear, the lamp controlling relays, A, B, C and D are only energized when an impulse of heavy current is transmitted and thus the codes diagrammatically shown give an indication of which lamp controlling relays will be energized. For instance, in the numerical code, the series of impulses for the digit 6 consists of, first, a heavy positive impulse, second, a heavy negative impulse, third, a light positive impulse and fourth, a heavy negative impulse. As indicated, the relays A, B and D will be energized through this code. The stations code, since a smaller number of selections have to be made, never has a heavy current impulse for the last impulse and therefore only three lamp controlling relays A, B and C are provided, the last light negative impulse being merely for switching purposes.

The particular action of the relays as effected by the sending of these code impulses will be more fully explained herein-after.

95 It is believed that the invention will best be understood by describing the method of establishing a connection from a calling substation as shown at 101, to a called substation as shown at 102. When the calling subscriber removes his receiver from its switch-hook, a signal (not shown), is lighted at the A operator's position. This operator thereupon connects the cord circuit conductors 103 and 104 to the calling line manually or by any other suitable means. As soon as the A operator has connected a cord circuit to the calling line, a cord finder, whose brushes are indicated at 105 and 106 operates to connect an idle sending device to the cord circuit taken for use.

When the A operator connects the cord circuit to the calling line she ascertains the number of the wanted subscriber and proceeds to set up this number on the keyboard 115 of her sending device.

Let us assume that the wanted number is four, five, six, seven, party W. The operator will then depress the corresponding stations, thousands, hundreds, tens and units 120 keys, in response to which the associated sequence switch registers will be moved and the stations register 109 will come to rest in position 4,—the thousands register 110 will stop in position 4, the hundreds register 125 111 in position 5, the tens register 112 in position 6, and the units register 113 in position 7.

It will be assumed that the automatic trunk selecting switch whose brushes are 130

indicated by the numerals 107 and 108 has been set to select the proper trunk for connecting the calling subscriber with the B operator's position at the office in which the wanted line terminates. It will also be assumed that the sequence switch associated with this trunk selecting switch has been moved into position 11.

After the sending device has been set and 10 when the trunk selecting switch has been operated to extend the calling line to the B operator's position at the desired office, the sequence switch associated with the cord finder will be in position 7, where a circuit 15 will be established to move the sequence switch 114 out of position 1. This circuit may be traced from grounded battery, magnet of the sequence switch 114, contact 115, contact 116 of the cord finder sequence 20 switch to ground. With sequence switch 114 in position 2, a circuit is closed from ground, winding of relay 117, contact 118, cord finder brush 105, contact 119, trunk selector brush 108, lower armature and back 25 contact of relay 120, winding 121 of the repeating coil, winding of relay 123, to grounded battery. Relays 117 and 123 are operated by current flowing over this circuit. At the armature and front contact of 30 relay 117 a circuit is closed to ground, through contact 124, magnet of the sequence switch 114 to grounded battery, to move this sequence switch out of position 2 and into position 3. At the front contact and 35 armature of relay 123 a circuit is closed from ground, through the left-hand back contact and armature of relay 125, the lamp 126, to grounded battery. Lamp 126, in lighting, indicates to the B operator that a 40 call is waiting attention and also indicates the trunk over which the call has been extended. The B operator thereupon depresses key 127 to associate a number indicating device with the trunk over which the 45 call has been extended.

Upon the depression of key 127 a circuit is closed from ground, winding of relay 120, contact of key 127, conductor 128, winding of relay 200 to grounded battery. Relay 200 attracts its armatures to apply ground to the various controlling leads of the number indicating device. At the same time the relay 120 attracts its armatures, and at its lower armature and back contact 50 interrupts the energizing circuit of relay 117. When this relay deenergizes it closes a circuit from ground, its armature and back contact, contact 129, magnet of sequence switch 114 to grounded battery, to move sequence switch 114 out of position 3 and 55 through its various operating positions back to position 1, during which a complete set of code impulses is transmitted to the relays 201, 202 and 203.

60 When sequence switch 114 moves into position

4 a circuit is closed from grounded battery through the low resistance 130, contacts 131, 132 and 133, cord finder brush 105 and contact 119, trunk selector brush 108, lower armature and front contact of 65 relay 120, conductor 134, winding of the positive polarized relay 201, winding of the negative polarized relay 202, winding of the marginal relay 203, conductor 204, upper front contact and armature of relay 70 120, trunk selector brush 107, contact 135, cord finder brush 106, contact 136 to ground. Since the impulse circuit extends through the low resistance 130 the marginal relay 203 is energized, and since this impulse is 75 positive, the relay 201 also attracts its armature. With these two relays energized the stations relay A is actuated over a circuit closed from grounded battery, left-hand winding of the relay A, conductor 205, left-hand armature and back contact of relay 206, left-hand back contact and armature of relay 207, left-hand front contact and armature of relay 203, right-hand front 80 contact and armature of relay 201, conductor 208, to ground at the armature of relay 200. Relay A is energized and at its right-hand front contact and armature completes a locking circuit for itself from grounded battery, through both its windings in series, 85 to ground over conductor 208.

In position $\frac{4}{2}$ of sequence switch 114 a current impulse of the opposite polarity is transmitted from grounded battery, low resistance 130, contacts 137, 138, 139, cord 100 finder brush 106, contact 135, trunk selector brush 107, upper armature and front contact of relay 120, conductor 204, winding of marginal relay 203, winding of the negative polarized relay 202, positive polarized relay 201, conductor 134, lower front contact and armature of relay 120, trunk selector brush 108, contact 119, cord finder brush 105, contact 140 to ground. In response to 105 this impulse the relays 202 and 203 are energized and attract their armatures.

The peculiar action and interactions of the relays 207 and 209 should be noted at this point. Relay 209 has two windings, the left one being marginal and used as a 115 holding winding after the armatures have been attracted by the energization of the right winding. When ground is first placed on the left armature of relay 209 relay 207 is energized in series with the left winding 120 of 209, but this left winding of relay 209 being marginal does not cause the attraction of the armatures of relay 209. Relay 207 is actuated and short-circuits the right-hand winding of relay 209.

Upon the removal of ground on the left armature of relay 209 the short circuit around the right winding of relay 209 is removed and it is therefore actuated in series with relay 207. When ground is again 130

- placed on the left-hand armature of relay 209 the winding of relay 207 and the right-hand winding of relay 209 are short-circuited and relay 207 becomes deenergized but 5 relay 209 remains energized through its left-hand marginal holding winding. When finally the ground on the left-hand armature of relay 209 is removed relay 209 becomes deenergized.
- 10 Thus, through two successive applications and removals of ground on the left-hand armature of relay 209 we have, first, an actuation of relay 207, second, an actuation of relay 209, third, a deenergization 15 of relay 207 and fourth, a deenergization of relay 209.

Going back now to the point where relays 202 and 203 were energized it will be noted that as soon as relay 202 attracted its armature it closed a circuit from grounded battery, left-hand winding of relay 209, winding of relay 207, left-hand back contact and armature of relay 209, front contact and armature of relay 202 to ground over conductor 208. The left-hand winding of relay 209 is a holding winding and operates to hold the armatures of this relay attracted when once they have been actuated by the right-hand or pull-up winding of 25 this relay. Thus the relay 209 does not attract its armatures, but the relay 207 does attract its armatures in this circuit. At the inner right-hand front contact and armature of this relay a break-point in the energizing circuit of right-hand winding of relay 209, is closed, but this winding is short-circuited at this time.

At the outer right-hand front contact and armature of relay 207, an energizing circuit 40 for relay 206 is completed from grounded battery, winding of this relay, inner left-hand back contact and armature of relay 210, through the armature of relay 207 to ground over conductor 208. Relay 206 attracts its armatures and at its inner right-hand front contact and armature closes an energizing circuit for the relay 210, but since this last mentioned relay is short-circuited at this time, it does not attract its 45 armatures.

Also in response to the actuation of relays 202 and 203 the stations relay B is energized over a circuit from grounded battery, left-hand winding of relay B, right-hand 55 back contact and armature of relay 210, outer right-hand back contact and armature of relay 209, right-hand front contact and armature of relay 203, front contact and armature of relay 202 to ground over conductor 208. The relay B attracts its armatures and at its right-hand front contact and armature completes a locking circuit for itself.

When the sequence switch 114 moves into 60 position 5 a heavy positive current impulse

is transmitted from grounded battery, low resistance 130, contacts 172, 141 and 133, over the circuit previously described to ground through contact 136. In response to this heavy positive current impulse the 70 relays 201 and 203 attract their armatures. At this time, however, the relay 202 becomes inert, so that the short circuit about the right-hand winding of relay 209 is removed and a circuit is completed from 75 grounded battery, through the left-hand winding of relay 209, winding of relay 207, right-hand winding of relay 209, inner right-hand front contact and armature of relay 207 to ground over conductor 208. 80 Since the right-hand winding of relay 209 is energized, this relay now attracts its armatures.

In response to this last impulse of heavy positive current the relay C is also energized over a circuit traceable from grounded battery, left-hand winding of relay C, outer right-hand back contact and armature of relay 211, outer right-hand front contact and armature of relay 206, left-hand front 90 contact and armature of relay 207, left-hand front contact and armature of relay 203, contact and armature of relay 201 to ground over conductor 208. Relay C attracts its armatures and through its right-hand 95 armature and front contact completes a locking circuit for itself. As soon as the relay 209 attracts its armatures the relay 210, which had previously been shunted, is energized over a circuit extending 100 from grounded battery, winding of relays 206 and 210, inner right-hand front contact and armature of relay 206, conductor 208, to ground.

In position 5½ of sequence switch 114 a 105 weak negative impulse is transmitted from grounded battery through high resistance 142, contact 139, over the circuit previously described to ground through contact 140. In response to this negative impulse the relay 202 only attracts its armature and thereby completes a holding circuit for the relay 209 from grounded battery, left-hand winding of relay 209, left-hand contact and armature of this relay, contact and armature of relay 202, conductor 208, to ground. The relay 207 is short-circuited and retracts its armatures. This completes the selection 115 of the stations lamp controlling relays.

Since the thousands register 110 has been 120 set in position 4, when the sequence switch 114 is moved into position 6 no heavy current impulse is transmitted but a light impulse is sent from grounded battery, through high resistance 142, contact 133, 125 over the circuit previously described to ground through contact 136. In response to this impulse the relay 202 deenergizes to cause the release of the relay 209. At this time the relay 201 energizes, but since 130

the marginal relay 203 is not also energized, its actuation is of no avail.

In position $6\frac{1}{2}$ of sequence switch 114 a strong negative impulse is transmitted from 5 grounded battery, through the low resistance 130, contacts 143, 144 and 139, over the circuit previously described to ground through contact 140. In response to this impulse the relays 202 and 203 are energized and complete a circuit from grounded battery, left-hand winding of relay B' (Fig. 4), conductor 300, inner right-hand back contact and armature of relay 213, right-hand front contact and armature of relay 10 210, outer right-hand contact and armature of relay 209, right-hand front contacts and armatures of relays 203 and 202 to ground over conductor 208. Relay B' attracts its armatures and completes a locking circuit for itself from grounded battery, through both of its windings in series, its right-hand front contact and armature, conductor 301, inner left-hand front contact and armature of relay 200 to ground. 15 25 In response to the energization of relay 202 the relay 207 is again energized over a circuit extending from grounded battery, left-hand back contact and armature of relay 209, front contact and armature of relay 202 to ground over conductor 208. Relay 207 attracts its armatures to prepare at its inner right-hand front contact and armature an energizing circuit for the relay 209, and at its outer right-hand front 20 30 35 contact and armature completes an energizing circuit for the relay 211 from grounded battery, winding of this relay, inner left-hand back contact and armature of relay 213, inner left front contact and armature of relay 210, outer right-hand contact and armature of relay 207 to ground over conductor 208.

With the sequence switch 114 in position 7 only a weak positive impulse is sent since 45 the register contact 145 is not closed in position 4. In response to the weak positive impulse only the relay 201 is energized. The relay 202 deenergizes and the right-hand winding of relay 209 is no longer 50 shunted but is energized over a circuit traceable through grounded battery, left-hand winding of relay 209, winding of relay 207, right-hand winding of relay 209, inner right-hand front contact and armature of relay 207, conductor 208 to ground. 55 Since this impulse is weak, none of the thousands lamp controlling relays are now actuated.

With the sequence switch 114 in position 60 $7\frac{1}{2}$, a heavy negative impulse is transmitted from grounded battery, through the low resistance 130, contacts 146, 147 and 139, over the circuit previously described, to ground through contact 140. In response to this impulse relays 202 and 203

are energized, and relay 202 completes a holding circuit for relay 209 from grounded battery, left-hand winding and front contact and armature of relay 209, the front contact and armature of relay 202 to ground 70 over conductor 208. The relay 207 is thereby shunted and retracts its armatures. In response to the operation of relays 202 and 203 an energizing circuit is completed for relay D' from grounded battery, left-hand winding of this relay conductor 302, outer right-hand back contact and armature of relay 213, outer left-hand front contact and armature of relay 210, outer right-hand front contact and armature of relay 209, right-hand front contact and armature of relay 203, right-hand front contact and armature of relay 202 to ground over conductor 208. Relay D' attracts its armatures and completes a locking circuit for itself 75 80 over conductor 301. This completes the selection of the thousands lamp controlling relays.

Remembering now that the hundreds register 111 is set in position 5, it will be 90 seen that in position 8 of sequence switch 114, a weak positive impulse is transmitted from grounded battery, through high resistance 142, contact 133, over the circuit previously described to ground through 95 contact 136. In response to this impulse the relay 202 retracts its armature to effect the deenergization of the relay 209. The relay 209 retracts its armatures and the relay 213, previously shunted, is actuated 100 over the circuit traceable from grounded battery, winding of relay 211, winding of relay 213, inner right-hand front contact and armature of relay 211, conductor 208 to ground. Since the marginal relay 203 105 is not energized, none of the hundreds lamp controlling relays are actuated.

In position $8\frac{1}{2}$ of sequence switch 114, however, a heavy negative impulse is transmitted from grounded battery, low resistance 130, contacts 148, 173 and 139, over the circuit previously described to ground through contact 140. In response to this heavy negative impulse relays 202 and 203 are energized. Relay 207 is again energized 110 over a circuit traceable from grounded battery, left-hand winding of relay 209, winding of relay 207, left-hand back contact and armature of relay 209, front contact and armature of relay 202, conductor 208, to 115 ground. As soon as relay 207 attracts its armatures, relay 214 is energized over a circuit from grounded battery, winding of relay 214, inner left-hand back contact and armature of relay 215, inner left-hand 120 front contact and armature of relay 213, inner left-hand front contact and armature of relay 210, outer right-hand front contact and armature of relay 207, to ground over conductor 208. Simultaneously with the 125 130

energization of relay 207, the relay B² is actuated over a circuit completed from grounded battery, left-hand winding of this relay, conductor 303, inner right-hand back contact and armature of relay 215, inner right-hand front contact and armature of relay 213, right-hand front contact and armature of relay 210, outer right-hand back contact and armature of relay 209, front contacts and armatures of relays 203 and 202, to ground over conductor 208. Relay B² attracts its armatures and at its right-hand front contact and armature completes a locking circuit for itself over the conductor 301.

With the sequence switch 114 in position 9 only a weak positive impulse is transmitted, since the register contact 149 is not closed in position 5. In response to this 20 weak positive impulse the relay 201 is energized and the relays 202 and 203 deenergize. The energization of relay 201 however is ineffective since the marginal relay 203 is inert, and none of the hundreds lamp 25 controlling relays actuated in response to this impulse. When the relay 202 is deenergized the relay 209 is operated over a circuit extending from grounded battery, left-hand winding of relay 209, winding of relay 207, right-hand winding of relay 209, inner right-hand front contact and armature of relay 207 to ground, over conductor 208.

Since contact 150 of the hundreds register 30 111 is not closed in position 5, only a weak negative impulse is transmitted when sequence switch 114 is moving through position 9½. In response to this negative impulse, relay 207 is short-circuited by the 35 actuation of relay 202 and a holding circuit is completed for the relay 209 from grounded battery, left-hand winding of this relay, left-hand front contact and armature of this relay, right-hand front contact 40 and armature of relay 202 to ground over conductor 208. This completes the selection of the hundreds lamp-controlling relays.

It will now be noted that the tens sequence 45 switch register 112 is set in position 6. With sequence switch 114 in position 10, a heavy positive impulse is transmitted from grounded battery, through low resistance 130, contacts 151, 152 and 133, over the circuit previously described, to ground through 50 contact 136. In response to the heavy positive impulse the relay 202 deenergizes and effects the deenergization of relay 209. Relays 201 and 203, however, are actuated to complete an energizing circuit for the tens 55 lamp controlling relay A³, conductor 304, outer right-hand contact and armature of relay 217, middle right-hand front contact and armature of relay 214, left-hand front contact and armature of relays 211 and 206, 60 left-hand back contacts and armature of re-

lay 207, left-hand front contact and armature of relay 203, right-hand front contact and armature of relay 201, to ground over conductor 208. Relay A³ attracts its armatures and at its inner right-hand front contact and armature completes a locking circuit for itself over conductor 301.

With the sequence switch 114 in position 10½ a heavy negative impulse is transmitted from grounded battery, low resistance 130, contacts 153, 154 and 139, over the circuit previously described to ground through contact 140. In response to this heavy negative impulse relays 202, 203 attract their armatures. Relay 207 is energized in a manner previously described and attracts its armatures to complete a circuit for the relay 217, from grounded battery, winding of this relay, inner left-hand back contact and armature of relay 218, inner left-hand front contacts and armatures of relays 215, 213 and 210, outer right-hand front contact and armature of relay 207 to ground over conductor 208. In response to the energization of relays 202, 203, the relay B³ is actuated over a circuit completed from grounded battery, left-hand winding of this relay, conductor 305, inner right-hand back contact and armature of relay 218, inner right-hand front contact and armature of relay 215, inner right-hand front contact and armature of relay 213, right-hand front contact and armature of relay 210, outer right-hand back contact and armature of relay 209, right-hand front contacts and armatures of relays 203 and 202 to ground over conductor 208. Relay B³ completes a locking circuit for itself from grounded battery, its two windings in series, its right-hand front contact and armature to conductor 301.

With sequence switch 114 in position 11 a weak positive impulse is transmitted from grounded battery, resistance 142, contact 133 over the circuit previously traced to ground at contact 136. This results in the deenergization of relays 202 and 203 and the energization of relay 201. The deenergization of relay 202 results as previously described, in the energization of relay 209. Since relay 203 is not energized at this time 110 the energization of 201 does not result in the selection of any one of the tens lamp controlling relays.

In position 11½ of sequence switch 114 a heavy negative current impulse is transmitted from grounded battery, resistance 130, sequence switch contacts 155, 156 and 139 over the circuit previously traced back to ground at sequence switch contact 140. This results in the deenergization of relay 120 201 and the energization of relays 202 and 203. In the manner previously described relay 207 becomes short-circuited and retracts its armatures. Relay D³ is thereupon 125 energized over a circuit including grounded 130

battery, the left-hand winding of relay D⁸, conductor 306, the outer right-hand armature and back contact of relay 218, the outer left-hand front contact and armature of relays 215, 213 and 210, outer right-hand front contact and armature of relay 209, right-hand front contact and armature of relays 203 and 202 to ground over conductor 208. Relay D⁸ attracts its armatures and completes a locking circuit for itself over conductor 301 to ground. This completes the selection of the tens lamp controlling relays.

It will now be noted that the units sequence switch register 113 has been set in position 7. When the sequence switch 114 is rotated through position 12 a heavy impulse of positive current is transmitted from grounded battery, low resistance 130, contacts 157, 158, 133, over the circuit previously described to ground through contact 136. In response to this impulse, relay 202 deenergizes to effect the deenergization of the relay 209 and the relays 201 and 203 attract their armatures. The deenergization of relay 209 results in the removal of the short circuit about relay 218 and it thereupon energizes. The units lamp controlling relay A⁴ is now energized over a circuit extending from grounded battery, left-hand winding of this relay, conductor 307, middle right-hand front contacts and armatures of relays 217 and 214, left-hand front contact and armature of relays 211 and 206, left-hand back contact and armature of relay 207, left-hand front contact and armature of relay 203, right-hand front contact and armature of relay 201 to ground over conductor 208. Relay A⁴ attracts its armatures and at its inner front contact and armature closes a locking circuit for itself over conductor 301.

In position 12½ of sequence switch 114, a heavy impulse of negative current is transmitted from grounded battery, low resistance 130, contacts 159, 160 and 139, over the circuit previously described to ground through contact 140. In response to this impulse the relays 202 and 203 attract their armatures. At the right-hand front contact and armature of relay 202 an energizing circuit is closed for the relay 207. Upon the actuation of the relay 207, a circuit is closed for the relay 219 from grounded battery, winding of this relay, the inner left-hand armatures and front contacts of relays 221, 218, 215, 213 and 210, outer front contact and armature of relay 207 to ground over conductor 208. In response to this last-mentioned impulse the relay B⁴ is also operated over a circuit traceable from grounded battery, left-hand winding of this relay, conductor 308, inner right-hand front contacts and armatures of relays 218, 215, 213, right-hand front contact and armature

of relay 210, outer right-hand back contact and armature of relay 209, right-hand front contacts and armatures of relays 203 and 202 to ground over conductor 208, whereupon relay B⁴ locks up to grounded conductor 301.

While the sequence switch 114 is rotated through position 13, a weak impulse of positive current is transmitted over the signaling circuit. In response to this impulse the relay 202 deenergizes and relay 201 is energized. When the relay 202 deenergizes the relays 207 and 209 again become energized in a series circuit which has previously been described. The actuation of relay 201 however does not effect the operation of any of the units lamp controlling relays since the marginal relay 203 is not operated at this time.

In position 13½ of sequence switch 114 a weak impulse of negative current is transmitted over the signaling circuit. Relay 202 in response to this impulse attracts its armatures to complete a circuit through the holding winding of relay 209 and shorts circuits the relay 207. Since the marginal relay 203 is not operated the relay D⁴ is not actuated.

As sequence switch 114 passes out of position 13½ the signaling circuit is opened and all three of the relays 201, 202 and 203 become deenergized. In response to the retraction of the armature of relay 202, relay 209 becomes deenergized and at its inner right-hand armature and contact opens the short circuit about the relay 221, which thereupon becomes energized in series with the relay 219 through the inner right-hand armature and front contact thereof.

When the relay 217 operated it closed a circuit from ground through its left-hand front contact and armature, conductor 222, winding of relay 310 to grounded battery. This last-mentioned relay attracts its armatures to connect battery to the various relays which control the lighting of the thousands and hundreds digit lamps. When relay 221 attracted its armatures, at its outer left-hand armature and front contact it completed a circuit for energizing relay 223, to light the stations indicating lamp. At the outer right-hand armature and front contact of relay 221, a circuit is closed for lighting the selected units indicating lamps, and at the outer right-hand armature and front contact of relay 219 a circuit is closed for lighting the selected tens indicating lamps.

It will be remembered that the thousands digit lamp is No. 4 and that the relays B¹ and D¹ have been actuated and locked up. When the relay 310 attracts its armatures a circuit is closed from grounded battery, outer right-hand armature and contact of the relay 310, through the number 4 lamp, 130

contact 312 and armature of relay A¹, outer left-hand front contact and armature of relay B¹, inner right-hand front contact and armature of relay D¹ to ground over conductor 301. The circuits for lighting the hundreds, tens and units digits lamps may be similarly traced.

The stations lamp W will be illuminated upon the actuation of relay 223 through a circuit extending from grounded battery, the second right-hand armature and contact of relay 223, lamp W, outer left-hand armature and front contact of relay C, outer right-hand armature and front contact of relay A, left-hand armature and front contact of relay B to the ground on the outer right-hand armature of relay 223.

It will be understood that as soon as the impulse transmitting device 114 has completed its operation the cord finder, whose brushes are designated by the characters 105 and 106, as well as the associated sequence switch, is restored to normal. At the same time a sequence switch, only certain of the contacts of which are shown associated with a trunk selecting switch, is moved out of position 11 to open the contacts 119 and 135 and to close the contacts 164 and 165. The B operator upon noting the number of the wanted line inserts the plug 161 into a jack 162 of this line and depresses the proper ringing key 163 for applying suitable current to the calling line to ring the station W which appears on this line.

The B operator releases the key 127 and effects the deenergization of relays 120 and 200. When relay 200 retracts its armatures the operated relays controlling the number indicating device appearing on Figs. 2 and 3 are deenergized through the removal of ground from conductors 208 and 301 and the number indicating device is placed in condition to indicate a second wanted number.

The insertion of the plug 161 into jack 162 completes a circuit for relay 125 which upon energization causes the lighting of lamp 126 through a circuit from grounded battery, lamp 126, armature and front contact of relay 125, armature and back contact of relay 123 to ground.

On retraction of the armatures of relay 120 a circuit is closed from grounded battery, winding of relay 123, winding 121 of the repeating coil, lower back contact and armature of relays 120, trunk selector brush 108, contact 164, conductor 104, through the calling substation apparatus 101, conductor 103, contact 165, trunk selector brush 107, upper armature and back contact of relay 120, winding 166 of the repeating coil, winding of relay 167 to ground. Relays 167 and 123 are energized in this circuit and the movement of the armature of relay 123 causes the extinguishing of lamp 126 which thereby indicates to the B operator that the

calling subscriber is properly connected to the selected trunk.

At the close of the conversation, when the calling subscriber hangs up his receiver, a signal (not shown) is operated at the A operator's position and this operator proceeds to release the trunk selecting switch and other selector switches employed in the connection. When these switches are released the circuit for the relays 123 and 167 is opened and the lamp 126 is lighted to inform the B operator that the call has terminated. This operator then removes plug 161 from jack 162.

It will thus be seen that the invention as employed in a telephone system comprises a series of number indicating lamps, one series of lamps for each character of the largest number to be indicated. These series of lamps are selectively controlled by sets of relays A¹, B¹, C¹, D¹; A², B², C², D², etc., each of these sets of relays being variably operated in succession by impulses of current transmitted over a metallic signaling circuit comprising two sides of the trunk circuit in series, and the conductors 134 and 204. The impulse sending device which transmits impulses over the metallic signaling circuit consists of a sequence switch 114 and the contacts of the various operator controlled registers designated ST, TH, H, T and U. The mentioned means for operating the sets of lamp relays in succession consists of a series of switching relays 210, 213, 215, 218 and 221. These switching relays as well as the lamp controlling relays are variably operated in response to impulses from the transmitting device.

It will be noted that a continuous series of weak positive impulses and weak negative impulses would have been produced if none of the sequence switch register contacts had been closed through the agency of the high resistance 142 and the combination of sequence switch contacts 133, 136, 139 and 140. Such a series of impulses would alternately energize relays 201 and 202 and in response to such action the relays 207 and 209 would be energized and deenergized in the manner hereinbefore described. Such interactions would cause the successive operation of relays 206, 210, 211, 213, 214, 215, 217, 218, 219 and 221. Hence the series of weak impulses control the sequence of operation of the digits' indicators.

The impulses of heavy current are, through the agency of the low resistance 130 and the various sequence switch cams of the registers, superimposed on the impulses of light current. The function of the impulses of heavy current is, as has been seen from the previous description, to control the energization of the lamp controlling relays so that there is present a means for sending one series of impulses to control 130

the sequence of operation of the indicators and a means for simultaneously sending a second series of impulses for controlling the individual indicator.

5. It will be understood that this disclosure is merely typical of applicant's invention and that its use is not limited to number indicating arrangements in automatic telephone systems or even to telephone systems 10 broadly.

What is claimed is:

1. In a telephone exchange system, an operator's position, an indicating device thereat, a trunk line comprising talking 15 conductors extending to said position, means to selectively operate said indicating device by impulses of current differing in polarity, a variably operable register and means for impressing impulses upon the 20 talking conductors of said trunk line to control said indicating device in accordance with the setting of said register.

2. In a signaling system, an indicating device comprising several indicators each 25 arranged to be variably operated, a switching means comprising relays for controlling the sequence of operation of said indicators, a signaling circuit over which said indicators are controlled, and means for impressing 30 impulses thereon of certain characteristics to control said switching means and for impressing impulses of other characteristics to operate said indicators.

3. In a signaling system, an indicating 35 device comprising several indicators each arranged to be selectively operated, means including a train of relays operated in response to positive and negative impulses for controlling the sequence of operation of 40 said indicators, a signaling circuit over which said indicating device and switching means are controlled, and means for transmitting current impulses of the proper characteristics over such circuit to control said 45 indicating device and switching means.

4. In a telephone system, an operator's position provided with an indicating device, a second operator's position, a trunk line interconnecting said positions, an impulse 50 sending device at said second position for transmitting current impulses of different polarity over the two conductors of said trunk line in series to control said indicating device.

5. In a telephone system, an operator's position provided with an indicating device, a second operator's position, a trunk line interconnecting said positions, and an impulse sending device at said second position 55 for transmitting impulses of various strength and polarity over said trunk line to control said indicating device.

6. In a telephone system, a telephone line, an impulse transmitting device connectable 60 to said line for transmitting impulses of

positive and negative polarity thereover, and a number indicating device controlled by impulses transmitted from said sender over two sides of said line in series.

7. In a telephone exchange system, a sending device, a plurality of variably adjustable registering devices included in said sending device, a line, an impulse transmitting device connectable to said line for transmitting impulses of varying strength thereover in 70 accordance with the positions assumed by said registering devices, and a number indicating device controlled by impulses transmitted from said transmitting device over the two sides of said line in series. 80

8. In a telephone system, a number indicating device, a signaling circuit over which impulses are transmitted to control said indicating device, an impulse sender of the sequence switch type for transmitting impulses 85 varying in strength over said circuit, and manually controlled registers for variably controlling the operation of said impulse sender.

9. In a telephone system, a number indicating device comprising a set of lamps and lamp controlling relays for each character of the largest number to be indicated, said relays being variably controlled in response to impulses of current of positive and negative polarity, a signaling circuit over which said impulses are transmitted, and means associated with said circuit for generating 95 said impulses.

10. In a signaling system, the arrangement of two relays and a circuit arrangement including a contact point whereby two successive closures and openings of said contact point will cause said relays to be successively actuated in all possible combinations. 100

11. In a signaling system, the arrangement of two relays and a circuit therefor including a contact point whereby successive closures and openings of said contact point 110 will cause said relays to intercontrol one another in such manner that said relays are periodically actuated in various combinations substantially as described.

12. In a signaling system, the arrangement of a relay with a single winding, a relay with a plurality of windings, and a circuit arrangement including a contact point whereby successive closures and openings of said contact point will cause said relays to 120 be successively actuated in various combinations substantially as described.

13. In a signaling system, the arrangement of two relays and a circuit arrangement therefor including a contact point 125 whereby a closure of said contact point will cause one relay to be actuated, a subsequent opening of said contact point will cause the other relay to be actuated, a subsequent closure of said contact point will cause said 130

first relay to be deenergized, and a subsequent opening of said contact point will cause said second relay to be deenergized.

14. In a signaling system, the arrangement of a relay with a single winding, a relay with a plurality of windings, and a circuit arrangement therefor including a contact point whereby the closure of said contact point will cause said relay with a single winding to be energized, an opening of said contact point will cause said relay with a plurality of windings to be energized, a subsequent closure of said contact point will cause said relay with a single winding to be deenergized and a subsequent opening of said contact point will cause said relay with a plurality of windings to be deenergized.

15. In a signaling system, the arrangement of two relays, one being provided with a single winding and the other with a plurality of windings, and a circuit arrangement including a contact point whereby successive closures and openings of said contact point will cause, first, the energization of said single winding relay, second, the energization of said double winding relay, third, the deenergization of said single winding relay, and fourth, the deenergization of said double winding relay.

In witness whereof, I hereunto subscribe my name this 24th day of September A. D., 1918.

EDGAR H. CLARK.
